[57] CLAIM

The ornamental design for a combined big game drag
rope and handle, as shown and described.

DESCRIPTION

FIG. 1 is a top and side perspective view of a combined
big game drag rope and handle showing my new design;
FIG. 2 is a cutaway elevational view thereof;
FIG. 3 is a front elevational view thereof;
FIG. 4 is a rear elevational view thereof;
FIG. 5 is a top plan view thereof, the bottom being plain
and unadorned; and,
FIG. 6 is a side elevational view thereof, the side oppo-
site being a mirror image of the side shown in FIG. 6.
The rope is shown broken away in FIGS. 1-6 to indicate
that it is of indeterminate length.
